MATERIAL HANDLING APPARATUS

Erwin E. Franz, Cranford, N. J., assignor to Western Electric Company, Incorporated, New York, N. Y., a corporation of New York

Application December 10, 1941, Serial No. 422,398

5 Claims. (Cl. 29—89)

This invention relates to material handling apparatus, and more particularly to apparatus for holding in proper juxtaposition members to be secured together as a unitary structure.

In modern telephone central apparatus as well as in many other kinds of electrical apparatus, coils comprising a laminated magnetic core having two stacks of laminae put together to make a loop or closed magnetic circuit and having a winding on one side of this loop or ring-shaped core, are used in vast numbers. The two stacks composing the core may be secured together by means of external tie pieces and bolts passing through the tie pieces and stacks of laminae. These assembly bolts may also secure other members of the assembly in place, such as bases or terminal supports or other members.

An object of the present invention is to provide a simple, reliable and effective apparatus to receive and hold in precisely predetermined juxtaposition and relation to each other a set of parts which are to be secured together into a unitary assembly.

With the above and other objects in view, the invention may be embodied in an apparatus comprising a bed to support perforated members to be assembled, a pair of positioning members approximable to each other in the plane of the bed to receive therebetween and position on the bed members to be assembled, clamp members carried by the positioning members and reciprocable therein perpendicularly to the bed to clamp members to be assembled in place on the bed, a second pair of positioning members approximable to each other in the plane of the bed in a direction at right angles to the motion of the first pair of positioning members, positioning pins in the bed at right angles to the plane thereof to be received in the perforations of the members to be assembled and reciprocable to be withdrawn therefrom, and a cam having members conformed to actuate the several movable elements mentioned in predetermined time sequence.

Other objects and features of the invention will appear from the following detailed description of one embodiment of the invention, taken in connection with the accompanying drawings in which the same reference numerals are applied to identical parts and in which

Fig. 1 is a plan view of an apparatus constructed in accordance with the invention and shown in open or receiving position;

Fig. 2 is a vertical transverse section on the line 2—2 of Fig. 1;

Fig. 3 is a horizontal section on the line 3—3 of Fig. 2;

Fig. 4 is a broken partial view similar to Fig. 2 but on an enlarged scale and showing the parts in closed position;

Fig. 5 is a view similar to Fig. 1 with the parts in closed position and a horizontally-sectioned unit to be assembled in place;

Fig. 6 is a broken, vertical section on the line 6—6 of Fig. 5;

Fig. 7 is a broken, horizontal section on the line 7—7 of Fig. 2;

Fig. 8 is a detached, plan view of the coil unit to be assembled in the apparatus; and

Fig. 9 is a detached, exploded view of the components of the coil unit.

In the embodiment of the invention herein disclosed to illustrate the invention, a flat, horizontal, base member 20, a cylindrical vertical wall member 21, and a flat, horizontal top member 22 suitably secured together form a generally cylindrical or drum-shaped housing adapted to be stationarily secured on a suitable table or other support (not shown) by means of perforated angle lugs 23.

A pair of similar carriage blocks 24 and 25 is mounted in radial slots in the top 22 to be slideable therein toward and from each other. Since these two blocks are substantially identically alike, not only in themselves but also in the associated parts and members carried by them and movable with as well as in some cases relatively to them also, only one of them will be described and provided with reference numerals in detail, namely 25, the lower one in Fig. 1 which is also the one at the right in Fig. 2. Minor differences in proportion will be pointed out in due course.

On the under side of the block 25 is rigidly secured a depending tube or sleeve 26 coaxial with a vertical bore 27 in the block 25. A vertically slideable rod 28 is housed and guided in the sleeve 26 and bore 27 and is surrounded by a compression spring 29. The rod 28 is prevented from rotation by a key 30 entering a coacting vertical groove or keyway 31 in the rod.

A cross-head 32 is rigidly and radially mounted on the upper end of the rod 28, and a relatively light compression spring 33 tends to keep the cross-head and rod 28 up. The radially inner end of the head 32 is formed with an overhanging clamp member 34. The radially outer end of the head 32 is forked to receive and be guided by a guide rod or pin 35, rigid in a corresponding vertical bore in the block 25 to assist in keeping the cross-head in rigidly radial alignment.

Because of differences in dimensions at the two ends of the unit to be assembled in the apparatus, the block 24 is somewhat higher than the block 25, its vertically slideable rod 28 somewhat longer, and its clamping member 134 on its cross-head somewhat longer; but in general structure and action the two blocks and their associated parts are alike.

A generally disc-like cam 36 is mounted under, spaced a little from and parallel to the top 22 of the housing, to be rotatable to and fro about the axis of the housing to which the blocks 24 and 25 are relatively radially movable. The sleeve 26 of the block 25 and the corresponding sleeve of the block 24 pass through respective cam track slots 38 and 37 in the cam 36, best shown in Fig. 3. The cam, manually actuatable by a lever 39 and handle 40, when rotated will draw the blocks 24 and 25 together or force them apart in accurately predetermined motion.

Just under the cam plate 36, a vertically disposed cam roller 41 is mounted on a horizontal support slideable on the rod 28. This roller coacts with a vertically-acting cam member or surface 42, secured or formed on the under-side of the plate 36, as best shown in Fig. 3. The corresponding roller 43 and cam member 44 associated with the block 24 are also shown in Fig. 4. When the cam track slots 37 and 38 cause the blocks 24 and 25 to move inwardly and as these approach their final positions, the cam members 42 and 44 draw the cross-heads 32 and 132 resiliently down by compressing the springs 29 and 129.

A two-part bed 45, 46 rests on the center of the top 22, the part 45 being rigidly held in place by pins 47 mounted in the top 22, and entering corresponding closely fitting bores in the part 45. Similar pins are provided for the part 46, but the bores in 46 into which these pins enter are enough larger than the pins to allow of some movement of the part 46 on the top 22. This movement is limited to a short reciprocability toward and from the part 45 by bolts 48 and a guide pin 49. Compression springs 50 normally hold the part 46 away from the part 45.

Vertically reciprocable pins 51 emerge forwardly from the part 45 near each end. The thicker integral shaft portions of these pins pass down through appropriate bores in the part 45 and in the top 22 and are supported by compression springs 52. Similar and similarly located pins rise from the part 46 and have their thicker shafts guided in slidably close fitting bores in the part 46 and pass down through the top 22 via enlarged bores to permit them to move with the part 46 toward and from the part 45. The pins 53 are also provided with springs 52. The left end of the part 45 (Fig. 7) extends out across the end of the part 46 and carries two vertical immovable pins 54. The bores in the parts 45 and 46 for the pins 51 and 53 are enlarged at the bed surface of the parts (as indicated only in Fig. 4) into hexagonal pockets 55 to receive article assembling nuts and hold them against rotation as hereinafter described. The top of the left end of part 45 (Fig. 4) is formed with an article base locating groove 56 oriented across the length of the part 45 and in which groove the pins 54 are located.

A pair of blocks 57 and 58 is supported on the top 22 to be reciprocably slideable toward and from each other in a direction at right angles to the lengths of the bed parts 45 and 46 and

to the line of reciprocation of the blocks 24 and 25. The block 58 is provided across its inner end with an integral or rigidly attached cross clamp member 59. A similarly shaped clamp member 60 is mounted to be limitedly slideable on the block 57 in the direction of its length and reciprocation and is held yieldably in its leftmost position (Fig. 6) on the block 57 by a compression spring 61. Each of the blocks 57 and 58 is provided on its under-side with a cam pin or collar 62 and 63 respectively which engage in and are driven respectively by cam slots 64 and 65 in the cam 36.

The cam 36 is also provided with clearance slots 66 for the pins 51 and 53 and with cam members 67 to draw the pins 51 and 53 down against the tension of the springs 52.

In Fig. 9 are shown in an exploded view, the component parts of the particular article selected to illustrate the use of the apparatus described above as an illustrative embodiment of the invention. This article is shown in Fig. 8, assembled as it comes from the apparatus. The particular article illustrated is an electrical coil used by the thousand in telephone apparatus. It is shown in Fig. 9 in the components for assembling which the present apparatus is designed. These components are a plain stack 66 of L-shaped laminae of magnetic metal, a similar stack 67 having on it a winding 68 of insulated wire, a block 69 of insulating material molded on the stack 67 and having metal terminals 70 for the winding embedded in the block 69. There is also an insulating washer 71. The unit consisting of the parts, 67, 68, 69, 70 and 71 will be indicated for convenience by the single number 72. The principal members of the completed articles are the two units 66 and 72. These are to be spaced apart by laminae 73 of insulating material, and secured together by a support 74, three identically similar ties 75, and four identically similar bolts 76 with nuts 77. The support 74 is a roughly T-shaped member of metal, shown in plan in Figs. 8 and 9, and in side elevation in Fig. 4.

With the apparatus in the position shown in Figs. 1 and 2, the four nuts 77 are dropped down over the four pins 51 and 53 and rest in the pockets 55. The pins are slightly smaller in diameter than the holes in the nuts, and the pockets are shaped and dimensioned to receive the nuts easily and hold them against rotation. The support 74 is placed on the pin 51 and the pin 53 at the left in Fig. 2. The flat, square, vertical base member of the support fits into the groove 56 and between the pins 54 in the stationary bed part 46 and is thus positively located on the bed. One of the ties 75 is placed on the other pin 51 and other pin 53 at the right in Fig. 2. The unit 72 is placed on the pins 51 and the stack 66 is placed on the pins 53. The squares 73 of insulation are dropped vertically into place between the stacks 66 and 67. The last two ties 75 are placed on the pins 51 and 53 transversely to the stacks. All the components are now approximately in place except the four bolts.

Then the handle 40 is moved from the solid line position of Fig. 1 to the dotted line position, thus rotating the cam 36. The cam slots 37 and 38 drive the blocks 24 and 25 radially inwardly and a positioning finger 78 on the block 24 slips between the coil base or support 74 and the insulating winding head 69 and bottoms on the end 75 of the stack 67. At the same time the cam slots

64 and 65 drive the blocks 57 and 58 radially inwardly. The block 58 carries its rigidly attached cross-head 59 to a positively predetermined position in which the end portions of its inner face should and usually do make contact with the lower end (Fig. 1) of the outer face of the stack 67 and with the outer faces of the lower ends of the terminals 70. The various holes in the stacks, support and ties through which the pins 51 and 53 pass are all a little larger than the pins, so that these various parts have some play on the pins. The cross-head 59 also has at its lower end a forwardly projecting positioning arm 79 which slides over and positions the lower end face of the stack 67. Meanwhile, the cross-head 60, which is resiliently mounted on the block 51, has been pressed against the stack 66 and has pressed this against the insulators 73 and the stack 67, and has received and located the stack between its positioning arms 80.

The pair of stacks is now located vertically by resting on the bed 45, 46. It is located horizontally and longitudinally of the stacks by the finger 78 and the arms 79 and 80. It is located horizontally and transversely of the stacks by the rigid cross-head 59 and the resilient cross-head 60. The cross-head 60 is made resilient to allow different thicknesses of the insulating squares 73 to be used when it is desired to modify the magnetic circuit of the coil.

Toward the latter part of the inward travel of the blocks 24 and 25, the cam members 42 and 44 begin to draw down the cross heads 32 and 132. The cam parts are so arranged that the clamp members 34 and 134 do not touch the ties 75 on the stack ends until the cross-heads 59 and 60 have positioned the stacks. Then the clamp members come down on the ties and clamp the entire assembly as shown in Fig. 4. As the clamps move down, the cam members 167 draw the pins 51 and 53 down into the position shown in Fig. 4. The bolts 76 are dropped down behind the retracted pins and screwed into the nuts 77, completing the assembling operation.

The handle 40 is then brought back to its original position. As the clamps begin to rise, the cross-heads 59 and 60 also release their grip, and the pins 51 and 53, rising, strike against the ends of the bolts 76 and so knock out the completed article in case any of the nuts 77 have jammed a little in the sockets 55.

Details of proportion of the several positioning and clamping means will of course be varied to suit other articles of like general character to be assembled. The embodiment described is illustrative and may be variously modified and departed from while remaining within the spirit and scope of the invention as pointed out and described in the appended claims.

What is claimed is:

1. Assembling apparatus for assembling parts comprising a bed to receive parts to be assembled, a pair of positioning devices reciprocable toward each other in the plane of the bed to engage parts on the bed, a second pair of positioning devices reciprocable toward each other in the plane of the bed at an angle to the path of reciprocation of the first mentioned devices to also engage parts on the bed, a movable member having cam slots into which operating portions of the devices project and a handle for moving the member to cause the cam slots to reciprocate the devices to engage and thereby position the parts to be assembled.

2. Assembling apparatus for assembling parts

comprising a bed to receive parts to be assembled, a pair of positioning devices reciprocable toward each other in the plane of the bed to engage parts on the bed, a second pair of positioning devices reciprocable toward each other in the plane of the bed at an angle to the path of reciprocation of the first mentioned devices to also engage parts on the bed, a movable member having cam slots into which operating portions of the devices project, clamping arms carried by certain of the positioning devices, cams carried by the movable members, and a handle for moving the member to cause the cam slots to reciprocate the devices to engage and thereby position the parts to be assembled and to cause the cams to engage portions of the arms to move the arms in a path at an angle to the plane of the bed to clamp the positioned parts.

3. Assembling apparatus for assembling perforated parts comprising a bed to receive and support such parts, a movable pin passing through the bed at right angles to the plane thereof, spring means associated with the pin to normally project the pin to be received in the perforations of parts placed on the bed, a pair of positioning devices reciprocable toward each other in the plane of the bed to engage the parts on the bed, a movable member having a cam portion and cam slots, and a handle for moving the member to cause the cam portion to engage with and thereby withdraw the pin against the spring means to allow assembly fastening elements to be placed in the perforations and the cam slots to engage portions of the positioning devices and thereby move the devices into engagement with and position the parts therebetween.

4. Assembling apparatus for assembling perforated parts comprising a bed to receive and support such parts, a movable pin passing through the bed at right angles to the plane thereof, spring means associated with the pin to normally project the pin to be received in the perforations of parts placed on the bed, a pair of positioning devices reciprocable toward each other in the plane of the bed to engage the parts on the bed, clamping arms carried by the device, a movable member having cam portions and cam slots and an operating handle for moving the member to cause one of the cam portions to engage and thereby withdraw the pin against the spring to allow fastening elements to be placed in the perforations of the parts, other cam portions to engage portions of the clamping arms to cause the arms to clamp the parts upon the bed and the cam slots to engage portions of the positioning devices to reciprocate the devices into engagement with the parts upon the bed.

5. Assembling apparatus for assembling perforated parts comprising a bed to receive and support perforated parts to be assembled, reciprocable pins passing through the bed at right angles to the plane thereof, a spring surrounding each pin to normally project the pin to be received in the perforations of parts placed on the bed, a pair of positioning devices reciprocable toward each other in the plane of the bed to engage the parts on the bed, a second pair of positioning devices reciprocable toward each other in the plane of the bed at right angles to the path of reciprocation of the first mentioned devices to also engage the parts on the bed, clamping arms carried by the first mentioned positioning devices, spring means associated with the arms to normally project them from the bed,

a cam plate rotatably supported underneath the bed and having cam slots and cam portions, and an operating handle attached to the plate for rotating the plate and thereby in timed sequence causing the cam slots to engage depending portions of the positioning devices to cause the devices of each pair to approach each other and

engage the parts on the bed, engaging certain of the cam portions with depending parts of the clamping arms to withdraw them against their springs means until the arms clamp the parts, and engaging other cam portions with the pins to withdraw them against the surrounding spring.

ERWIN E. FRANZ.
